(57) **CLAIM**

I claim the ornamental design for a hand carriable vacuum cleaner, as shown and described.

DESCRIPTION

FIG. 1 is a perspective view from the front and one side of the hand carriable vacuum cleaner;

FIG. 2 is a perspective view from the rear and the other side of the hand carriable vacuum cleaner of FIG. 1;

FIG. 3 is an elevational view of one side of the hand carriable vacuum cleaner of FIG. 1;

FIG. 4 is an elevational view of the other side of the hand carriable vacuum cleaner of FIG. 1;

FIG. 5 is a front elevational view of the hand carriable vacuum cleaner of FIG. 1;

FIG. 6 is a rear elevational view of the hand carriable vacuum cleaner of FIG. 1; and,

FIG. 7 is a top plan view of the hand carriable vacuum cleaner of FIG. 1.

The parts in stippled outline do not form part of the design.
